POWER DRIVEN AIR CIRCULATING FAN

Edward J. Frick, Fairview Park, Ohio, assignor
to Air Controls, Inc., Cleveland, Ohio, a corpora-
tion of Ohio

Application September 23, 1950, Serial No. 186,389

3 Claims. (Cl. 230—259)

1

This invention relates to ventilating fans, and more particularly, to power-driven fans adapted to be readily inserted in a window frame, or carried from room to room.

An object of this invention is to provide an electrically operated ventilating fan adapted to be placed in a window in a vertical position or placed in various parts of a room in a horizontal position.

Another object is to provide a fan construction permitting adequate flow of air to the fan blades, when it is disposed in horizontal position on a floor or other surface, as well as, when it is disposed in a vertical position.

Other objects are, to provide means for retaining the fan in position at the bottom of a window sash, which means are also adapted to be used as a handle in carrying the fan; to provide a neat and attractive protective grille around the sides of the fans, to provide a relatively light weight fan adapted to be readily carried from room to room, to provide an attractively designed fan for a wide range of uses; and to provide a fan which is of simple durable construction and adapted to be produced at a relatively low cost.

These and further objects will appear in the course of the following specification.

In the drawings forming a part of this specification:

Fig. 1 is a front elevational view of one embodiment of my invention, showing the fan in vertical position;

Fig. 2 is a side view corresponding to Fig. 1;

Fig. 3 is a rear elevational view corresponding to Fig. 1.

Fig. 4 is a top plan view; while

Fig. 5 is a central section of the fan taken on the line 5—5 of Fig. 2, showing the fan disposed in horizontal position.

In the drawings the numeral 11 indicates a base, crimped along three sides forming a flange 12, while the front margin is provided with an integral offset portion 13. A top member 14, corresponding in construction to the base 11 includes a similar flange 15, extending along three sides and a similar offset portion 16, while a front face member 17, extending from the base 11 to the top 14, is provided with rearwardly extending flange 18 crimped over the offset portion 13 of the base 11. The top margin of the face member 17 is provided with a similar flange 19 crimped over the offset portion 16 of the top 14. Spot welding or other suitable means may be used to unite offset portion 13 to the flange 18 and offset portion 16 to the flange 19.

2

The front face member 17 is provided along its sides with flanges 20 formed by a crimping operation. Centrally the face member 17 is provided with a circular opening 21, having an outwardly projecting flange 22 along its periphery, as illustrated in Figs. 2, 4 and 5. A circular front grille 23, of reticulate construction, formed of a series of crimped wires disposed at right angles to each other and woven together is of convex configuration when mounted on the fan. A rim 24, having a rolled over bead portion 25 retaining the outer periphery of the grille 23 is provided with a flange 26 adapted to be received in the outer periphery of the flange 22 of the face member 17 and retained by a pressed fit.

A similarly formed reticulate wire grille 27, constituting the sides and back of the fan, having its bottom and top margins positioned inwardly of the bottom and top flanges 12 and 15 respectively, and suitably secured thereto, has its side margins positioned inwardly of the face flanges 20 and suitably secured thereto by means of cap screws 28 clamping the grille between strips of metal 39 and the flanges 20. Obviously, different types of protective grille material may be used to accomplish the same purpose.

An electric motor 29, bolted to vertically extending brackets 30 suitably secured to the top 14 and base 11, drives a fan 31 comprising four wide blades 32, formed of sheet metal, terminating centrally in a hub 33 mounted on a shaft 34 driven by said motor. This direct drive construction has been found to be advantageous over belt or gear driven construction. Preferably a permanently lubricated motor is used, and if desired, a two-speed control may be provided.

Two spaced handles 37, provided with rubber pads 38 secured to bolts and cooperating parts, operating in transverse slots in the top member 14, are positioned and arranged in such manner that they may be spaced apart a distance corresponding with the width of a window sash, thus permitting a window sash to be lowered between them, and in this manner the fan may be supported in a window frame in a vertical position. The handles 37 may be moved in close proximity to each other to provide a convenient handle by which the fan may be carried.

For supporting the fan in a vertical position short rubber tipped feet 35 projecting downwardly from the base 11 are provided, while similar feet 36 projecting outwardly from the back of the fan provide support when the fan is disposed in a horizontal position, as illustrated in Fig. 5. Attention is directed to the location and

arrangement of the back feet 36. The two feet at the top thereof are secured to the top flange 15, while the lower two feet are secured to the base flange 12. Thus it will be seen that the top and base flanges 15 and 12 serve to retain the edges of the grille 27 in position, and in addition thereto function to support the fan while in a horizontal position. If desired a vertically disposed reenforcing strip 40 extending from the top flange 15 to the bottom flange 12 and suitably secured thereto, may be provided to prevent warping or bulging of the grille 27.

As shown in Fig. 5, when the fan is in a horizontal position on a floor or table the disposition and arrangement of the grille 27 permits air to flow into the fan through the sides and back thereof, thereby permitting an unobstructed flow of air into the fan, as indicated by the arrows. The position and arrangement of the feet 36 and the motor supporting brackets 30 are such that the entire weight of the motor 29 is carried on the brackets 30, leaving no load to be supported by the grille 27, which might bend or injure it.

It will be apparent to those skilled in the art that the embodiment of my invention disclosed herein may be variously changed, used or modified without departing from the spirit of the invention, and that this embodiment of my invention is illustrative only, and that my invention is not limited thereto.

I claim:

1. A portable electric fan including, a casing formed of relatively thin material having top and bottom walls formed of relatively thin sheet material, a front wall also formed of thin sheet material secured to said top and bottom walls and provided with an opening to permit air to pass therethrough, a continuous reticulate grille forming the side and rear walls of said casing, a rigid elongated motor support means secured to the opposed forces of said top and bottom walls, a motor secured to said support means and disposed between said front and rear walls in close proximity thereto, fan blades operatively connected to said motor, and feet projecting from the margins of said top and bottom walls for supporting said fan in a horizontal position on the rear wall with the fan axis perpendicularly disposed, said motor support means being positioned and arranged in such manner that it remains unflexed when the fan is thus disposed, whereby said motor is securely and rigidly supported in close proximity to said front and rear walls and said motor support means braces said top and bottom walls when the fan rests on the rear wall.

2. A portable electric fan including, a casing formed of relatively thin sheet material having top, bottom walls, the top and bottom walls being provided with marginal flanges on their sides and rear edges, a front wall also formed of thin sheet

5

material secured to said top and bottom walls, provided on its sides with rearwardly extending flanges and provided centrally with an opening to permit air to pass therethrough, a continuous reticulate grille forming the sides and rear walls of said casing and having its upper margins retained within said top wall side and rear flanges and its lower margins retained within said bottom wall side and rear flanges and its side margins retained within said front wall rearwardly extending flanges, a rigid elongated motor support means secured to said top and bottom walls, a motor secured to said support means and disposed between said front and rear walls in close proximity thereto, fan blades operatively connected to said motor, and feet projecting from said top and bottom marginal flanges for supporting said fan in a horizontal position on the rear wall, said support means being positioned and arranged in such manner that it remains unflexed when the fan is thus disposed whereby said motor is securely and rigidly supported in close proximity to said front and rear walls.

3. A portable electric fan including, a casing formed of relatively thin sheet material having top, bottom walls, the top and bottom walls being provided with marginal flanges on their sides and rear edges, a front wall also formed of thin sheet material secured to said top and bottom walls, provided on its sides with rearwardly extending flanges and provided centrally with an opening to permit air to pass therethrough, a continuous reticulate grille forming the side and rear walls of said casing and having its upper margins retained within said top wall side and rear flanges and its lower margins retained within said bottom wall side and rear flanges and its side margins retained within said front wall rearwardly extending flanges, a rigid elongated motor support means secured to said top and bottom walls, a motor secured to said support means between said front and rear walls on the side thereof toward the fan blades, fan blades operatively connected to said motor, and feet projecting from said top and bottom marginal flanges for supporting said fan in a horizontal position on the rear wall, said motor support means being positioned and arranged in such manner that it remains unflexed when the fan is thus disposed and braces said top and bottom walls whereby said motor depends from said support means when the fan is disposed on its rear wall and is rigidly supported in this position.

EDWARD J. FRICK.
